UNITED STATES PATENT OFFICE.

CHARLES WURTEMBERG, OF UNION CITY, CONNECTICUT, ASSIGNOR TO THE GOOD-YEAR'S METALLIC RUBBER SHOE COMPANY, OF NAUGATUCK, CONNECTICUT, A CORPORATION OF CONNECTICUT.

WATER-BOTTLE AND CLOSURE-PLUG ASSEMBLING MACHINE.

Application filed March 25, 1925. Serial No. 18,336.

To all whom it may concern:

Be it known that I, CHARLES WURTEMBERG, a citizen of the United States, residing at Union City, county of New Haven, State of Connecticut, have invented certain new and useful Improvements in Water-Bottle and Closure-Plug Assembling Machines, of which the following is a full, clear, and exact description.

10 This invention relates to a water bottle and closure plug assembling machine, more particularly to a machine for assembling the elastic threaded stopper receiving plugs in rubber receptacles such as hot water bottles, ice bags, etc.

Rubber receptacles such as hot water bottles are now largely made by a molding process in which the body of the bottle is molded and cured and the core then removed from the interior of the bottle by stretching the neck and withdrawing the core through it. It then becomes necessary to insert in the neck of the bottle a threaded closure plug in which the stopper of the bottle may be inserted in use. Various methods of inserting the plug have been tried, among which are cementing the plug in by means of a quick-curing cement, which method requires the use of molds around the neck of the bottle during the curing operation, while another method consists in cementing the plug in place and then wrapping the outside of the bottle neck with wire and afterward covering the wire with a strip of rubber. These methods are objectionable by reason of the expense, time, and labor required, and more recently a better method has been disclosed in the patent to Randall & Pierce No. 1,484,407, November 7, 1922. This patent discloses a method and machine by which an elastic stopper receiving plug is constricted by an appropriate device and inserted in the neck of a water bottle or similar receptacle, around the exterior of which neck has been previously disposed a constricting ring. After the constricted plug has been aligned with the exterior ring the plug is freed from the constricting device and allowed to expand, thereby firmly gripping the neck of the bottle between itself and the exterior ring. This method and machine have proved very satisfactory in practical use as compared with the methods previously employed for securing the plugs,

but the machine is manually driven and certain of the operations must be manually performed.

An object of the present invention is to provide an improved machine for positioning elastic plugs in openings in receptacles.

Another object is to provide a machine of this character in which the manual labor is reduced to a minimum.

Another object is to provide a machine in which the plug is automatically disconnected from the holder by which it is inserted after it has been positioned in the receptacle.

Without intention to limit the invention otherwise than as required by the prior art, the same consists in a machine having a movable holder for detachably receiving an elastic plug, a device for constricting the plug prior to locating it in the receptacle, a positioning device for the receptacle, and power driven means for actuating the plug holder and constricting device and for automatically disconnecting the holder from the plug after insertion.

For a detailed disclosure of the invention reference is had to the accompanying specification and drawings, in which latter—

Fig. 1 is a front elevation of the machine;

Fig. 2 is a side elevation with parts broken away;

Fig. 3 is a top plan;

Fig. 4 is an enlarged sectional detail of the automatic means for disconnecting the plug holder from a plug;

Fig. 5 is an enlarged sectional detail illustrating the operation of the machine;

Fig. 6 is a section on the line 6—6 of Figure 5;

Fig. 7 is a central longitudinal section through the machine partly broken away; and

Fig. 8 is a detail of a clutch mechanism for the drive means.

Referring to the drawings, the numeral 1 designates the base of the machine, on the forward portion of which are disposed side frames 2 and 3. At the rear of the base is an electric motor 4, the shaft of which carries a pulley 5 which by means of the belt 6 drives a pulley 7, and on the shaft of the latter is a gear 8 meshing with a gear 9 freely rotatable on the main shaft 10 of

the machine. The belt 6 is kept taut by means of any suitable counter-weighted idler pulley 6^a. In order to operatively connect the gear 9 to the shaft 10 a clutch mechanism is provided, which, as it forms no part of the present invention, will be but briefly described. Rigidly mounted on the shaft 10 is a clutch housing 11 (Figures 3 and 8) which is provided with a peripheral groove 12 which may be engaged by the cam lever 13 resiliently urged into the groove by the spring 13^a. Adapted to extend across the groove 12 is a spring pressed clutch dog 14 having a groove adapted to register with the groove 12. When the cam lever 13 is withdrawn the dog moves forwardly and engages a slot in the gear 9 to operatively connect the latter to the shaft 10. In order to at will withdraw the cam lever 13 and permit the clutch dog to function said lever is provided with a yoke or bracket 15 the ends of which are secured to the cam lever 13 to form a retaining guideway for a cam release bar 16 operable by the pull rod 17. The bar 16 is provided with a notch 18 engageable by one end of the yoke 15. As shown in Figure 8 the release bar 16 is urged to the left and into engagement with the yoke by the coil spring 19. Also formed on the clutch housing is a release dog 20, and when the cam lever 13 has been withdrawn to allow dog 14 to clutch the gear 9 to shaft 10 and rotate the latter, the release dog 20 after making a half revolution strikes the release bar 16, thereby throwing it to the right and freeing the cam lever 13, which thereupon engages the groove 12 and withdraws the dog 14 from the gear 9. In order to quickly stop the shaft 10 pivotally mounted brake shoes 21 are provided which are pressed by the spring 22 to continuously engage a braking surface on the clutch housing. It is obvious that any other suitable form of clutch may be used.

Mounted on the shaft 10 is a cam 23 (Figure 2), with which engages a cam follower 24 carried at one end of a lever 25 pivoted to the frame 3 at 26, and the other end of the lever is connected by an adjustable link 27 to a slide block 28 (Figure 7) vertically movable in a slideway 29 formed by the frames 2 and 3 and the retaining plates 30. Rigid with the slide 28 is a tubular plug constricting device 31, and it will be noted from Figures 5 and 7 that the wall of this tube tapers to a thin edge at its lower end, while the bore of the tube also tapers to a smaller diameter at its lower end. Surrounding the constricting device 31 is a funnel-shaped guide or positioning device 32 for the neck portion of the receptacle, which latter in the specific disclosure is a hot water bottle. This guide is provided with slotted side brackets 33 by which

it may be adjustably secured, in the present instance, to the retaining plates 30 by the wing nuts 34.

Also secured on the main shaft 10 is a second cam 35 having on its side face a cam groove 36 in which is movable a follower 37 mounted on one end of a bell crank lever 38 pivoted to the side frame 3 at 39. The opposite end of the bell crank lever is connected by an adjustable link 40 to a second or upper slide block 41 also movable in the slideway 29. Rigid with the slide block 41 is an extension 42 in which is mounted a spindle 43 having secured to its lower end a threaded receiver 44 for the stopper receiving plug which is to be inserted. At the upper end of the extension 42 a knob 45 is pinned to the spindle 43 for manually rotating the latter when the operator presents a plug to the receiver 44 for attachment thereto.

Also secured on the shaft 10 is a third cam 46, with the periphery of which engages a follower 47 mounted on a lever 48 pivoted to the frame 2 at 49, the follower 47 being held in contact with the cam 46 by a spring 48^a attached to the lever 48. The upper end of the lever 48 is provided with a pin 50 movable in a slot 51 in a lever 52, which lever is pivotally and slidably mounted on a bracket 53 by means of a pin 54 on the bracket passing through a slot 55 in the upper end of the lever. Slidable in the slide block 41 is a rack bar 56 carrying at its rear end a pin 57 engaging the slot 51 of lever 52. At its forward end the rack bar is provided with a rack 58 which cooperates with a pinion 59 rigid with one member 60 of a clutch, which member 60 is rotatable and slidable on the spindle 43. The other member 61 of the clutch is formed rigid with the knob 45 previously described. A coil spring 62 surrounds the reduced upper end of spindle 43 and tends to move the clutch member 60 into engagement with the complementary member 61 of the clutch. Pivoted on the slide block 41 is a lever 63 provided at one end with a yoke 64 surrounding the clutch member 60, while the opposite end of the lever is adapted to bear against an adjustable stop screw 65 mounted on frame 2 when the slide block 41 is in its upper position, and therefore when in this position the lever 63 is tilted to disengage the clutch members 60 and 61.

In operation the elastic stopper receiving plug 66 (Fig. 5) is disposed against the plug receiver 44 and the knob 45 manually rotated to thread the receiver into the plug. As at this time the parts are in the position shown in Figure 2, the knob 45 and clutch member 61 are separated from the clutch member 60 and can be readily rotated to attach the plug to the receiver. A confining ring 67 is then placed around the neck of a

water bottle 68 by passing it over the flexible funnel mouth of the bottle, and the bottle is pushed up with its funnel mouth disposed over the guide or positioning device 32 as shown in Figure 5. The operator then starts the machine, and as the shaft 10 rotates the cam 35 through the bell crank lever 38 moves the slide block 41 and attached parts downwardly, and it will be noted that as soon as this movement occurs and the lever 63 is freed from the stop screw 65 the spring 62 forces the clutch member 60 down into engagement with the clutch member 61. In the downward movement of the slide block 41 the plug 66 moves downwardly within the constricting device 31 and due to the tapering bore of the latter is gradually constricted until finally it comes to a stop opposite the confining ring 67 as shown in dotted lines in Figure 5. While a secure and water-tight joint between the plug and bottle neck can be obtained without the use of cement, considerable friction is caused by the downward movement of the plug 66 through the constricting device and it is therefore desirable to apply a small amount of cement to the periphery of the plug, which acts as a lubricant. As soon as the plug is in a position opposite the confining ring 67 the cam 23 actuates the lever 25 to move the lower slide block 28 upwardly, this movement of said block carrying the constricting device upwardly, thereby freeing the plug 66 and allowing it to expand against the inner wall of the bottle neck opposite the exterior ring 67. The cam 46 then acts through the levers 48 and 51 and the rack bar 56 to rotate the pinion 59, and as the clutch members 60 and 61 are at this time in engagement the spindle 43 and plug receiver 44 are thereby rotated to disconnect the plug and the bag in which it is positioned from the receiver 44 and to force the bag downwardly. The slide blocks are then returned to the position shown in Figure 2 and the machine comes to a stop, whereupon the operations above described are repeated.

It will be seen from the above description that aside from securing the plug on the receiver 44 and holding the bottle neck up against the guide 32 no manual labor is required in the operation of the machine, and since the mechanism is power driven the operation of the machine is very much more rapid thereby resulting in an increased output. In the specific disclosure the machine has been shown as adapted for inserting plugs in oval-necked water bottles, but it is obvious that by suitably changing the constricting device 31 and guide 32, the machine may also be used for round-necked bottles, and it is not limited to the particular article shown but may be used wherever it is desired to insert elastic plugs of similar char-

acter into the necks or other openings in receptacles.

With the specific disclosure above given it is obvious that numerous modifications will suggest themselves to those skilled in the art, and it is therefore not desired to limit the invention otherwise than as set forth in the appended claims.

Having thus described my invention, what I claim and desire to protect by Letters Patent is:

1. A machine for attaching elastic stopper receiving plugs to the necks of receptacles comprising means for detachably holding a plug, means for inserting the plug in a receptacle while in constricted form, and automatic means for freeing the united plug and receptacle from the plug holding means.

2. A machine for attaching elastic stopper receiving plugs to the necks of receptacles comprising means for positioning a receptacle, relatively movable means for detachably holding, constricting, and inserting a plug, and automatic means for freeing the inserted plug and receptacle from the machine.

3. A machine for attaching elastic stopper receiving plugs to the necks of receptacles comprising means for positioning a receptacle, relatively movable and rotatable means for detachably holding, constricting and inserting a plug in the receptacle, and automatic means for relatively rotating the holding means and the united plug and receptacle to free the plug and receptacle from the machine.

4. A machine for attaching elastic stopper receiving plugs to the necks of receptacles comprising means for inserting a plug in a receptacle including a threaded plug holder, and automatic means for disconnecting the holder from the inserted plug.

5. A machine for attaching elastic stopper receiving plugs to the necks of receptacles comprising means for holding a plug, means for positioning a receptacle by its neck portion, and automatic means for inserting the plug in the receptacle neck while constricted and then releasing it and disconnecting it from its holder.

6. A machine for attaching elastic stopper receiving plugs to the necks of receptacles comprising rotatable and threaded means for holding a plug, means for positioning a receptacle, and automatic means for successively inserting the plug in the receptacle neck while constricted, releasing the plug, and rotating the plug holding means to disconnect it from the plug.

7. A machine for attaching elastic stopper receiving plugs to the necks of receptacles comprising a bodily movable and rotatable threaded plug holder, receptacle positioning means, a movable plug constricting device, a shaft, and means operatively

- connected to said shaft for successively bodily moving the plug holder and plug constricting device and rotating the plug holder.
- 6 8. A machine for attaching elastic stopper receiving plugs to the necks of receptacles comprising means for positioning a receptacle, means for detachably holding a plug, means for relatively moving said first 10 two means to dispose the plug in the receptacle neck, and automatic means for releasing the plug holding means from the plug.
9. A machine for attaching elastic stopper receiving plugs to the necks of receptacles comprising means for positioning a receptacle, means for detachably holding a plug, manually controlled power means for positioning the plug in the receptacle neck and means for automatically releasing the 15 plug holding means from the plug.
10. A machine for attaching elastic stopper receiving plugs to the necks of receptacles comprising means for positioning a receptacle, means for holding a plug, manually operable means for attaching a plug to said last means, means for disposing the plug in the receptacle, and automatic means for releasing the plug holding means from the plug.
11. A machine for attaching elastic stopper receiving plugs to the necks of receptacles comprising means for positioning a receptacle, means for holding a plug including a rotatable spindle having a plug receiving screw thread at one end, means for relatively moving said first two means to dispose the plug in the receptacle, manual means for rotating the spindle in one direction, automatic means for rotating the spindle in an opposite direction, and automatic 20 means for connecting or disconnecting the 25 30 35 40 45 50 55 60 65 70 75 80 85 90 95 100 105 110 115 120 125 130 135 140 145 150 155 automatic spindle rotating means and the spindle.

12. A machine for attaching elastic stopper receiving plugs to the necks of receptacles comprising means for positioning a receptacle, means for holding a plug including a rotatable spindle having a plug receiving screw thread at one end, means for longitudinally moving the spindle to insert the plug in the receptacle, manual means for rotating the spindle in one direction, automatic means for rotating the spindle in an opposite direction, and means governed by the longitudinal movement of said spindle for automatically connecting or disconnecting the automatic spindle rotating means and the spindle.

13. A machine for attaching elastic stopper receiving plugs to the necks of receptacles comprising means for positioning a receptacle, a longitudinally movable constricting device adapted to be disposed therein, a longitudinally movable rotatable spindle, a threaded plug receiver at one end thereof, manual means for rotating the spindle, power means for rotating the spindle, a clutch connecting the two, a shaft, cams carried thereby, operative connections between said cams and the spindle and constricting device for relatively longitudinally moving the two, an additional cam on said shaft, operative connections between the same and said power spindle rotating means, and means governed by the longitudinal movement of the spindle for controlling said clutch.

Signed at New Haven, county of New Haven, and State of Connecticut, this 17th day of March, 1925.

CHARLES WURTENBERG.
